DIFFERENTIAL JACK AND CARRIER

Bennett D. Monteith, Oklahoma City, Okla.

Application October 16, 1947, Serial No. 780,182

8 Claims. (Cl. 214—1)

1

This invention relates to improvements in a differential jack and carrier particularly arranged for lifting and carrying heavy differential housings for various types of trucks with comparative ease by a single mechanic with a saving of time and energy.

The primary object of this invention therefore is to provide such a jack and carrier structure which will enable a single mechanic to remove and replace the heavy differential assembly from any truck having a banjo type axle housing without enlisting the aid of others which operation has normally required several additional helpers. Accordingly the carrier may be placed in position under the differential housing, the jack raised, and the differential housing removed from the truck by one person with complete safety to the differential housing.

Another object of the invention is to provide a highly satisfactory and efficient jack structure for operation in such a jack and carrier combination.

Another object of the invention is to provide jig plates for engagement with various styles for different makes of trucks, in order that the differential jack and carrier may be used on any make of truck by the use of the proper jig plate.

Further objects and advantages will be apparent from the detailed description of highly practical forms of differential jack and carriers in accordance with my invention in the following specification, reference being made to the accompanying drawing forming a part thereof.

In the drawings:

Fig. 1 is a plan view of a differential jack and one form of carrier in accordance with my invention.

Fig. 2 is a side elevation thereof showing the carrier in an elevated position supporting a differential assembly.

Fig. 3 is a cross sectional view thereof taken on line 3—3 of Fig. 2.

Fig. 4 is a longitudinal sectional view thereof on line 4—4 of Fig. 1 taken in the direction of the arrows.

Fig. 5 is a similar longitudinal sectional view thereof on line 4—4 of Fig. 1 taken in the opposite direction.

Fig. 6 is a perspective view of the jack with a modified form of carrier supporting another type of differential assembly in accordance with my invention.

Fig. 7 is a plan view of the carrier shown in Fig. 6.

Fig. 8 is an end elevation of the same carrier.

2

Fig. 9 is a side elevation thereof.

Fig. 10 is a plan view of a further modified form of carrier in accordance with my invention.

Fig. 11 is an end elevation thereof and

Fig. 12 is a longitudinal sectional view taken on line 12—12 of Fig. 11.

Referring to the drawings in general my invention comprises a mobile differential jack 20 with a jig base plate 21 arranged to support a selected jig plate 22, 23, 24, or the like appropriate for engaging and supporting a differential assembly D_a, D_b or the like of an automotive vehicle, the jig plates 22, 23, 24 or the like being formed for the differential assembly it is to cooperate with, either through gravity cooperation or clamping engagement or the like with portions of the differential assembly.

As illustrated in Figs. 1 to 6 inclusive the mobile differential jack 20 comprises a substantially V-shaped base structure 25 preferably composed of hollow steel tubing or rod or shaft members of suitable weight and size the various metals or alloys of aluminum, magnesium or steel of I-beam angle iron or tubing may be employed. The members of this base may be formed in sections and welded or otherwise integrally connected with upper and lower metal plates 26 and 27 secured to the front end of base tubing sections 25 and angle plates 28 having lower side mounting elements 29 secured to the rear ends thereof. Lower front plate 27 and sides 29 of angle members 28 provide base structures upon which swivel ball bearing casters 30 are mounted as a three point movable support. By virtue of these casters the jack can always be made level even on uneven floor.

Jig base plate 21 is illustrated as a substantially rectangular structure bowed downwardly longitudinally. Jig base 21 is supported by means of three connecting link or radius rod elements. A radius rod element 31 is disposed at one side of the forward end of plate 21, and the other two radius rod elements 32 are disposed at the rear end thereof to support it adjacent the forward end of base 25, so that it can swing from a lowered compact position as shown in Figs. 4 and 5 to an operating upper position as best shown in Figs. 2, 3 and 6. Forward radius rod element 31 is mounted on a bearing 33 extending from a projection 34 on the upper plate 26 while the rear radius rod elements 32 are mounted on lower bearings 35 extending laterally from mountings 36 on the inner sides of the side base tube elements of base 25. The upper ends of radius rod elements 31 and 32 are journaled on bearings

37 and 38 respectively having bearing supports 39 and 40 on the under side of jig base 21.

By so mounting radius rod elements 31 and 32 with respect to the V-shaped base 25, that is as a parallelogram with the rear mountings lower than the front mounting, the jig base sets obliquely to the floor, as does the lower outline of most truck differential housings. The load is downward at all times. The shape of the base makes it almost impossible to overturn and the load is centered on the three casters with no tendency to rock. The upper carrier base 21 can be lowered into the base 25 when not in use.

To lift the upper carrier base plate 21 the mechanical advantage of a screw shaft 41 is used. A nut 42 is fastened to the bottom of the upper carrier base 21 by means of pivot 43 secured to the underside of the rear bearing support 40 at the rear underside of jig 21. Screw shaft 41 is provided with spaced stops 44 adjacent to its other end for anchoring the screw shaft in an eye 45 between the stops, eye 45 being in an elevated position above base 25 integrally secured to an arm 46 secured to and extending upwardly from plate 26 at the front end of base 25. Screw shaft 41 has a swivel handle 47 at its forward end for turning it for adjusting the upper base 21 to the desired height as a preferred and most convenient form of differential operating means in the jack altho other form jack operating elements could be used for raising or lowering the upper carrier base 21. It will be seen that with the jack operating screw shaft 41 as shown the upper carrier base 21 may be raised to any desired height or lowered into the jack base 25 so that a compact structure is provided when not in use and it is low enough so that it may be readily positioned under any of the usual differential assemblies.

Upper jig plate carrier base 21 is arranged to support jig plates for different types of commercial rear end assemblies now in use, comprising the jig plates 22, 23 and 24 heretofore referred to. Each of these plates has a slot 48 in its forward end and is formed with a central cylinder hinge bearing element 49 at its rear end. Base 21 has a forward vertical adjusting screw 50 at its forward end with a handle 51 at its lower end under plate 21 and an enlarged grooved upper end 52 into which the edges of the jig plate slot 48 are received. Lateral cylinder hinge bearing elements 53 extend from a plate 54 secured to the rear end of jig plate base 21 and a pintle or floating pin 55 provides a removable connection whereby any of the jig plates 22, 23 or 24 may be secured to this carrier base 21.

In general these jig plates all comprise slightly curved main body portions which conform somewhat to the curvature of the jig base plate 21 and more particularly with the different types of rear end assemblies. They are constructed with engaging elements for the various commercial differential housing assemblies with various types of notches, clamps, adjustable sockets and the like for gripping the assembly when the jack is positioned and adjusted in place with respect thereto. These jig plates may be formed so as to be preferably particularly applicable to a certain specific model of rear end assembly so as to have general or universal application.

As an example of a jig plate 22 for specific application to a differential assembly D_a outlined in the upper part of Fig. 2, a Timken type of rear end, the plate is provided with upwardly curved side arms 57 which have upper notches

58 which fit the lower studs 59 of the cross shaft cover plates 60 on the differential housing. At the front end of this Timken jig plate 22 as shown another support 61 is secured by a bolt 62 to the plate and having a slot 63 for length adjustment so that a collar 64 on the end of this support 61 can be slipped over the stud nut of the pinion housing of the Timken differential assembly. As shown in Fig. 1, plate 22 is apertured at 65 to receive a similar support and socket for a modified model of such Timken differential assembly. This jig plate 22 is likewise applicable to other rear end assemblies including Chevrolet Standard, Chevrolet, G. M. C., Eaton, International, as well as Timken and others.

In Figs. 6 to 9 inclusive I have illustrated a universal type of jig plate 23 which is shown specifically applied to Fig. 6 to a Timken third member assembly. This plate 23 has lateral arms 66 each with a longitudinal slot 67 thru which bolts 68 extend for holding upright clamp supports 69 in any desired position for universal application. Clamp supports 70 are mounted by means of pivot clamping bolts 71 in the upper ends of supports 69 so as to be angularly adjustable and together with the clamping bolts 68 for supports 69 universally adjustable with respect to plate arms 66 as well as adjustable inwardly and outwardly of these arms. Loose and rigid clamping plates 72 with clamping bolts 73 extend from clamp supports 70 and by means of the adjustments of the members they can be arranged to be clamped to rib flanges 74 of a differential assembly D_b as illustrated in broken lines in the perspective view, Fig. 6. This universally adjustable jig plate 23 is for use with numerous styles of rear end assemblies, the one indicated in the drawings being a Timken third member assembly.

Jig plate 24 illustrated in Figs. 10, 11 and 12 is a simplified construction similar to jig plate 23 but having clamping elements 74 extending inwardly from the upper ends of upwardly curved side members 75 extending from rear end of jig plate 24. As will be seen this jig plate is adapted for gripping rib flanges and the like of various differential assemblies.

I claim:

1. A differential jack and carrier comprising a portable jack including a substantially V-shaped base with wheels supporting the same providing a three point support, a jig plate base carried by said V-shaped base, a forward and two rear parallel links of substantially equal length pivotally connected with the under side of the jig plate base adjacent to the front and rear ends thereof, a pivot support for the lower end of the front link above the front of the V base, pivot supports for the lower ends of the two rear links in lower positions between the sides of the base to the rear of the front support, means for raising and lowering the same with respect thereto, a jig plate, means for mounting the jig plate on said jig plate base including a horizontal pivotal connection with the jig plate base at the rear thereof, said jig plate having a longitudinal slot at the front end thereof, an upwardly extending adjusting screw in the forward part of the jig plate base having its upper end formed to engage said slot in the jig plate, an operating handle on the lower end of said screw for operating the same for raising and lowering the front end of the jig plate with respect to the jig base plate, and means on said jig plate for engaging and holding an automotive rear end differential assembly.

2. A differential jack and carrier comprising, a portable jack including a V-shaped base, wheels at the end of said base providing a three point portable support, a jig plate base over said V-shaped base, a forward and two rear link supports for said jig plate base, pivotal connections between said links and the jig plate base and said V-shaped base providing a substantially parallel link connection with the forward link having its pivotal connections elevated with respect to the link connection of the pair of rear links with the V-shaped base, a rotatable screw extending rearwardly of the front end of the jack base, means on the front end of the screw for rotating the same, an upward support for said V-shaped base supporting the forward end of the screw and preventing relative longitudinal movement thereof, a nut movable on and movable by said screw connected with said jig plate base between the upper ends of said rear pair of link supports, a jig plate mounted on said jig plate base, and means on said jig plate for engaging and holding an automotive rear end differential assembly.

3. A differential jack and carrier comprising, a portable jack including a V-shaped base, wheels at the end of said base providing a three point portable support, a jig plate base over said V-shaped base, a forward and two rear link supports for said jig plate base, pivotal connections between said links and the jig plate base and said V-shaped base, a support on the front end of the V-shaped base for supporting forward link pivotal connection in an elevated position with respect to the jack base, supports for the pair of rear link pivotal connections extending laterally inward from the sides of the V-shaped base, a rotatable screw extending rearwardly of the front end of the V-shaped base, means on the front end of the screw for rotating the same, an upward support for said jack base supporting the forward end of screw and preventing relative longitudinal movement thereof, a nut movable on and movable by said screw connected with said jig plate base between the upper ends of said rear pair of link supports, a jig plate mounted on said jig plate base and means on said jig plate for engaging and holding an automotive rear end differential assembly.

4. A differential jack and carrier comprising, a portable jack including a substantially V-shaped base with wheels supporting the same providing a three point support, a jig plate base carried by said V-shaped base with means for raising and lowering the same with respect thereto, a jig plate mounted on said jig plate base, said mounting comprising complementing hinge cylinder elements on the rear of the jig plate base and jig plate, a removable hinge pintle connecting the same, and an adjustable support for the front end of said jig plate, laterally adjustable upright arms on said jig plate and clamping means carried at the upper ends of said arms for engaging and holding an automotive rear end differential assembly.

5. A differential jack and carrier comprising, a portable jack including a substantially V-shaped base with wheels supporting the same, providing a three point support, a jig plate V-shaped base carried by said base with means for raising and lowering the same with respect there-

to, a jig plate mounted on said jig plate base, said mounting comprising complementing hinge cylinder elements on the rear of the jig plate base and jig plate, a removable hinge pintle connecting the same, a screw extending upwardly through the front end of said jig plate base, an operating handle on the lower end of said screw, a circumferentially grooved head on the upper end of said screw, said jig plate having a slot in its front end so as to be removably engageable with the groove in the head on the upper end of said screw, laterally adjustable upright arms on said jig plate and clamping means carried at the upper ends of said arms for engaging and holding an automotive rear end differential assembly.

6. A differential jack and carrier comprising, a portable jack, a jig plate base carried by said jack, a jig plate removably connected to and supported by said jig plate base, and means on said jig plate for engaging an automotive differential housing comprising, lateral upwardly extending arms at the rear of said jig plate, and clamps pivotally mounted on the upper ends of said arms for engaging rib flanges of the differential housing.

7. A differential jack and carrier in accordance with claim 1 in which said differential housing holding means comprises lateral upwardly extending arms at the rear of said jig plate, means at the upper ends of said arms for engaging portions of differential housing comprising notches in the upper ends thereof which engage lower studs of the cross shaft cover plates of the differential housing, and a support with a collar on the front end of the jig plate for engaging a forward stud nut on the differential housing.

8. A differential jack and carrier comprising, a portable jack, a jig plate base carried by said jack, a jig plate removably connected to and supported by said jig plate base, and means on said jig plate for engaging an automotive differential housing comprising, lateral arms at the rear of said jig plates, said arms having longitudinal slots therein extending outwardly of the jig plate, supports extending upwardly from said arms, pivot bolts connecting said supports to said arms through said slots, clamp supports and clamps at the upper ends of said supports, and pivot bolts connecting said clamp supports to said upstanding supports.
